NIGHT LIGHT

John B. Scoby, 5423 Lancer Ave.,
Santa Maria, Calif. 93454

Filed July 5, 1966, Ser. No. 2,911

Term of patent 14 years

(Cl. D48—20)

Fig. 1

Fig. 2

FIG. 1 is a front elevational view of a night light showing my new design, and

FIG. 2 is a side elevational view of same.

The dominant features of my design reside in the portions shown in full lines.

I claim:

The ornamental design for a night light, substantially as shown and described.
